UNITED STATES PATENT OFFICE

ABRAHAM PERLMAN, OF NEW YORK, N. Y., ASSIGNOR TO A. PERLMAN IRON WORKS, INC., A CORPORATION OF NEW YORK

DOOR LOCKING AND OPERATING MECHANISM

Application filed May 22, 1931. Serial No. 539,292.

This invention relates to door locking and operating mechanisms, particularly to such mechanisms designed for use in connection with the cell doors in a prison, in which the cells are usually arranged in blocks of a number of cells.

The object of the invention is to provide a positive mechanically operated mechanism by means of which a selective operation of the doors may be effected by the keeper from any distant point, such as outside the corridor from a control box to which he has the key to render the mechanism accessible for operating the doors, which may be conveniently arranged and connected in groups and any one or more doors of one group or block, or of all groups, operated from the control box, either individually or simultaneously. Also, any one or more doors may be left unlocked or locked in their open position without interfering with the operation of the other doors.

To effect the above and other objects of the invention, which will appear from the description of the mechanism as shown in connection herewith, positive mechanical devices are employed, which are simple in construction and not easily tampered with or prevented from performing their required functions but which are easily operated by the authorized person, all of which will appear more fully in connection with the description of the operative embodiment of the invention illustrated in the accompanying drawings, showing the same as applied to one door of a group or block of cell doors of the sliding type.

In the drawings, like parts in the several views have been given the same reference numeral.

Figs. 1 and 1A are, together, a front elevation, partly in section, of a part of the operating mechanism and one of the doors, Fig. 1A being a continuation of the right hand end of Fig. 1.

Fig. 2 is an enlarged section view, taken on the line 2-2 of Fig. 1.

Fig. 3 is an enlarged sectional view, taken on the line 3-3 of Fig. 1.

Fig. 4 and Fig. 5 are fragmentary views

similar to Fig. 3 showing the mechanism in successive positions.

Fig. 6 is an enlarged sectional view, taken on the line 6-6 of Fig. 1A.

Fig. 7 is an enlarged detail view showing some of the parts of the mechanism of Figs. 3, 4 and 5 in perspective and separated.

Fig. 8 is a front view of the operating mechanism in the control box, located at the left of Fig. 1, and Fig. 9 is a sectional view of the same and being a continuation to the left of Fig. 1.

The mechanism will be described in connection with one of the cell doors, indicated at 1, and it will be understood that the same applies to the individual mechanisms provided for each door and which are operated from the control box selectively or simultaneously, as will be described.

The door frame 1 is provided with an extension 2 (Fig. 2) by means of which the door is suspended from a supporting bar 3, upon which are mounted rollers 4 riding upon a track 5 (Figs. 2, 3 and 4). These parts and the individual operating mechanisms are enclosed in a housing 6.

An actuating bar 9 extends above all of the doors of one group or block and is mounted upon rollers 10 and between side rollers 10' (Fig. 1). A rack 11 (Figs. 6 and 1A) is attached to the actuating bar 9 and is engaged by a gear 12, the operation of which will be described hereinafter in connection with the mechanism for operating the actuating bar to open and close the doors.

The actuating bar 9 is shown as rectangular in cross-section and hollow, to reduce its weight and provide the necessary rigidity.

Positioned above each door is a locking pin 14, carried by the actuating bar 9 and arranged to engage in a slot 16 in the supporting bar 3 from which the several doors are suspended individually. The locking pin is provided with a roller 17 at its lower end which rides upon the upper edge of the supporting bar 3. When this locking pin drops into the slot 16 for any individual door, that door is operatively connected with the actuating bar 9 for opening and closing.

The operating of the actuating bar 9 is

effected by means of a worm gear 18 (Figs. 1A and 6) mounted upon a shaft 19 to which the gear 12 is also attached. A worm 20 engages the worm gear 19 and is mounted upon and rotated by the shaft 21, which shaft extends to the left and into the control box (Figs. 8 and 9). At the end of the shaft 21 is mounted a sprocket 22 operated by a sprocket chain 23 from a lower sprocket 24, mounted on a shaft 25, upon the outer end of which is mounted an operating wheel 26, provided with a handle 27. The several sprockets and gears are proportioned so that one and one-half turns of the operating wheel 26 effect a longitudinal movement of the actuating bar 9 sufficient to move the door or doors, connected thereto by the locking pin or pins 14, from closed to open position, or vice-versa.

20 The position of the operating handle 27 indicates when the said door or doors are open or closed, as shown in Fig. 8.

A hand wheel 30 (Figs. 8-9), designated as the small hand wheel, is mounted on a shaft 31, to the opposite end of which is attached a sprocket 32 operating a chain 33 which, in turn, operates an upper sprocket 34 on the end of the shaft 35 (Figs. 1, 1A, 8 and 9). This shaft 35 extends above all of the doors of the group or block and upon the same is mounted a dog 36, one for each individual door, (Figs. 2, 3, 4, 5 and 7). Each dog 36 is provided with an extension 36' positioned to engage a boss 37 on a locking member 38.

35 The locking member 38 is loosely mounted on the shaft 35 and is provided with bosses 39 and 40 positioned to engage a lug 41 on the locking dog 42, which latter is mounted upon a shaft 43, one for each door, the locking dog 42 being provided with another lug 44 also positioned to be engaged by the boss 40 on the locking member 38. A stop lug 45 on the locking member 38 limits the movement thereof.

40 Referring to Figs. 3, 4 and 5, a latch operating plate 50 is mounted for vertical movement on guide pins 51 and 52 and is provided with a finger 53 positioned to engage a latch 54, pivotally mounted at 55 upon a carrier 56, which is pivotally mounted at 57 and provided with a second finger 58 positioned to be engaged by a co-operating finger 59 on the locking member 38, the operation of which will be explained.

45 An individual door control disk 60 is provided with a notch 61, the notch being differently positioned on the several individual disks for each door, which disks are mounted upon a shaft 62 (Figs. 1, 1A, 2, 3, 4, 5, 8 and 9). This shaft 62 is provided at its end which projects into the control box (Figs. 8 and 9) with a gear 63 meshing with a gear 64 at the upper end of a shaft 65, at the lower end 50 of which is mounted a gear 66 meshing with

a gear 67 operated by and mounted upon a sleeve 68 rotatably and loosely mounted upon the shaft 31. At the outer end of this sleeve 68 is mounted a dial wheel 69 upon which the individual door numbers are indicated and adjacent which is positioned an indicator 70 for determining the individual door to be operated.

To open all doors of the group or block simultaneously, the small hand wheel 30 (Figs. 8 and 9) is rotated to first bring the indication letter "O" to the top, rotating the same to the right as indicated by the arrow adjacent thereto. The wheel 30 is then rotated to bring the letter "D" to the top.

This operation of the hand wheel 30 rotates the shaft 35 and the several dogs 36, rotating the several members 38, as heretofore described, and moving the several locking dogs 42 from the locked position shown in Fig. 4 to the unlocked position shown in Fig. 3 and permitting the several locking pins 14 to drop into the slots 16, connecting the several doors with the actuating bar 9.

45 The door operating wheel 26 (Figs. 8 and 9) is now rotated by means of the handle 27, in the direction of the arrow, one and one-half turns to bring the handle 27 from the indication "Lock" to the indication "Open" (Fig. 8). This rotates shaft 21 with the worm and gear mechanism (Fig. 1A and Fig. 6) and moves the actuating bar 9 longitudinally and slides the doors to the open position. To close the doors, this operation is reversed, as will be understood.

50 To lock the doors when closed, the hand wheel 30 is rotated to the left to bring the letter "L" to the top and then to bring the letter "D" to the top, which moves the parts from the position shown in Fig. 3 to that shown in Fig. 4, in which position the locking dogs 42 are engaged in the slots 16 and the locking pins 14 are raised out of engagement therewith.

To operate any single door, bring the dial wheel 69 (Figs. 8 and 9) to position with the number of the desired door under the opening marked "A" in the indicator 70. This rotates sleeve 68, gears 67 and 66, shaft 65, gears 64 and 63, and control disk 60 (Fig. 4), bringing the notch 61 on the disk 60 for the desired door under the pointed end of the latch 54, which drops into this notch, as indicated in dotted outline in Fig. 4. Now the small hand wheel 30 (Fig. 8) is turned to the right bringing the letter "B" thereon under the indicator 70. This rotates shaft 31 (Fig. 9), sprocket 32, chain 33, sprocket 34, shaft 35 and dog 36, causing lug 36' to disengage the latch plate 50 and the finger 53, previously engaged with the latch 54, as shown in Fig. 5, allowing the latch to drop into the notch 61 in the disk 60, as shown in Fig. 4 in dotted outline. The large wheel 69 is now moved to bring the number of the door being oper-

ated from its position under the opening "A" in the indicator 70 (Fig. 8) to a position under the opening marked "C" in said indicator 70. This rotates shaft 62 and disk 60 and moves the latch 54 engaged therein, as described, moving the latch carrier 56 and causing its finger 58 to engage the finger 59 on the locking member 38, operating the same to move the locking dog 42 to its open or unlocked position, as shown in Fig. 3, and permitting the locking pin 14 to drop into engagement with the slot 16 and connecting the particular door with the actuating bar 9, which is operated in the same manner, by rotating the operating wheel 26, as described for the operation of all doors.

By bringing the small wheel 30 to position with the letter "O" under the indicator, thus releasing the latch 54 from the disk 60, the same operation can be repeated for any number of individual doors, thus connecting any desired number of doors with the operating mechanism for opening or closing.

The individual locking dogs for each door are mounted on a shaft 43, one shaft for each door. At the opposite ends of this shaft a second locking dog is mounted and positioned opposite the position of the slot 16 in the door support 3 when the door is in open position. This locking dog is indicated at 42' in Figs. 1 and 2 and moves with the shaft 43 and locking dog 42, both of which are mounted thereon.

When it is desired to lock any door in its open position, it is only necessary to operate the mechanism in the same manner as described in order to lock all doors, namely, move the small hand wheel 30 to bring the letter "L" under the indicator and then bring the letter "D" to the top, thus swinging the locking dogs 42 and 42' into locked position. The second locking dog 42' then takes the position shown in dotted outline in Fig. 2, entering the slot 16 in the door or doors which may be open, as will be understood.

It is desired in some cases to provide for locking the door frame at both top and bottom and in that case the locking dog 42' is provided with an extension arm 81 (Fig. 2) which engages one end of a lever 82, pivoted at 83. The opposite end of this lever 82 engages a second lever 84 positioned at right angles thereto (Fig. 1) and pivoted at 85 with its opposite end engaged with a link 86, the lower end of which is offset and arranged to enter a slot at 87 (Fig. 2) in the bottom portion of the door frame. Thus when the lever is operated by the locking dog being swung into its locked position this link enters the slot at 87 and also locks the door frame at this point.

Indicators are provided in the control box 7 (Fig. 8) to show which doors are open. These indicators comprise a number of slides, 65 corresponding to the number of doors, one of

which is numbered 90, the operation of which is described as illustrative of all the others. This slide may have a red spot which when the door corresponding thereto is open is

brought opposite an opening 91 by the action of the spring 92, as shown in Fig. 9. The slide is connected by a cable or wire 93 to

one end of a bell-crank lever 94, the opposite end of which is connected by another wire 95, which may be a sliding strip, (Fig. 1), connected by a link 96 to a slide 97 operated by

a lever 98 when the lower end thereof, 99, is disengaged from the upper edge of the door support 3 by the opening of the door. Other

doors are each connected in the same manner to separate sliding strips, corresponding to

95, operated in the same manner. The links 95, are interchangeable, as will be noted.

The operation of the operating wheel 26 (Figs. 8-9) by means of the handle 27 to move the actuating bar 9 and the doors connected thereto to open or closed position has been described. It is often desirable to provide for locking the doors in intermediate positions and to accomplish this in a simple manner the handle 27 is slideable in the operating wheel 26 and when slid inwardly indicated by the dotted position (27a) in Fig. 9, the inner end thereof enters one of the openings, 28, 28', 29, 29', etc., in the inner wall 7a of the control box 7 and prevents the operating wheel 26 from being moved by attempting to force the door (or doors) connected to the actuating bar 9 by the locking pin 14.

Openings, as indicated at 28 and 28', (Fig. 8) thus serve to lock the operating wheel and connected mechanism in closed and open positions, respectively, and other openings, such as indicated at 29 and 29', provide for locking the doors, by locking the actuating bar 9 and operating wheel 29, in any number of intermediate positions.

The sliding handle 27 also has another function, to prevent the operator from closing the door 8 (Fig. 9) of the control box 7, if the handle 27 is left in its unlocked or outer position, projecting beyond the door opening, as shown in full lines, but when pushed inwardly, to its dotted position, 27a, with its inner end engaged in one of the openings and locking the cell doors, as described, the control box door 8 can then be closed.

What I claim as new and desire to secure by Letters Patent is:—

1. Door locking and operating mechanism of the class described comprising the combination with a number of cell doors each independently mounted and adapted to be moved into open or closed position, of an actuating bar extending adjacent and adapted to be operatively connected to a predetermined number of said doors, a plurality of locking pins carried by said actuating bar

each adapted to operatively connect one of said doors with said actuating bar, a separate locking dog for each of said doors pivotally mounted and adapted to be swung into position to selectively disengage said locking pin therefrom and to lock said door against movement, a shaft extending adjacent all of said locking dogs, a plurality of operating dogs, one for each door, attached to said shaft, a plurality of locking members loosely mounted on said shaft and each positioned adjacent and adapted to be engaged and operated by one of said operating dogs and adapted to engage and operate one of said locking dogs, a hand wheel provided with position indications thereon operatively connected to and adapted to rotate said shaft to effect the operation of the aforesaid associated members, and means for effecting a longitudinal movement of said actuating bar to open and close said doors.

2. Door operating and locking mechanism of the class described comprising the combination with a number of cell doors each independently mounted and adapted to be moved into open or closed position, of an actuating bar extending and adapted to be operatively connected to a predetermined number of said doors, a separate locking pin for each of said doors adapted to connect said door to said actuating bar, a separate locking dog for each of said doors pivotally mounted and adapted to be swung into position to selectively disengage said locking pin therefrom and to lock said door against movement, a shaft extending adjacent all of said locking dogs, a separate operating dog for each of said locking dogs fixed upon said shaft, a separate locking member for each of said operating dogs loosely mounted upon said shaft adjacent and adapted to be operated by said operating dog and to operate said locking dog, means for rotating said shaft to effect the operation of said associated members, a plurality of individual door control disks each mounted adjacent and in operative relation to one of said locking members, a plurality of pivotally mounted latch carriers each positioned in operative relation to one of said control disks and adapted to selectively engage and operate one of said locking members, a plurality of latch members each mounted upon one of said latch carriers and adapted to selectively engage said control disk and operate said latch carrier and locking member associated therewith to effect a selective operation of said locking dogs, a plurality of latch operating plates each positioned in operative relation to one of said latches and adapted to be selectively operated by said operating dog, a shaft upon which said control disks are mounted, means for rotating said shaft to predetermined positions to bring any selected control disk into operative position to be engaged

with said latch to operate the said latch carrier and associated members and effect said selective operation of said locking dog controlled thereby, and means for effecting a longitudinal movement of said actuating bar to open or close any predetermined number of doors operatively connected thereto.

3. Door locking and operating mechanism of the class described comprising the combination with a number of cell doors each independently mounted and adapted to be selectively moved into open or closed position, of an actuating bar extending adjacent and adapted to be operatively connected to a predetermined number of said doors, a plurality of locking pins carried by said actuating bar each adapted to operatively connect one of said doors therewith, a plurality of pivotally mounted locking dogs each adapted to be swung into position to disengage one of said locking pins from said door and to lock said door thus disengaged against movement, a second group of locking dogs each operated simultaneously with one of said first named locking dogs and to lock one of said doors in its open position, an auxiliary locking bar operated by one of said last named locking dogs adapted to lock the lower portion of one of said door frames against movement, said locking dogs being arranged in pairs mounted on a connecting shaft, separate connecting shafts for each pair of locking dogs, selective operating means for effecting the operation of a predetermined number of said locking dogs and associated parts and adapted to effect the operation of any one or more of said doors, and means comprising a rotary handle operating connected shafts and a worm gear and rack connected to said actuating bar to cause a longitudinal movement thereof to open or close the said doors selectively connected thereto and means for locking said rotary handle and connected mechanism in any one of a number of intermediate positions.

4. Door locking and operating mechanism of the class described comprising in combination therewith a number of cell doors each independently mounted and suspended from a support extending on either side thereof, a lever engaging said support when said door is in its closed position and released therefrom when said door is opened, a slideable member operated by the movement of said lever and operatively connected with an indicator, one indicator and associated parts being provided for each door and independently operated thereby, an actuating bar provided with means for operative connection with a predetermined number of said doors, means for moving said actuating bar to open or close the doors connected therewith, means for selectively connecting any desired number of said doors with said actuating bar, and means for locking the doors not connected

therewith against movement in either closed or open position.

5. Door locking and operating mechanism of the class described comprising the combination with a number of cell doors adapted to be moved into open or closed position, means for selectively connecting any one or more of said doors with an actuating bar, an actuating bar for operating said doors connected thereto, means for locking said doors selectively in open or closed position, controlling means associated with said locking means whereby said doors may be selectively locked or unlocked in either open or closed position, means for operating said actuating bar, and means for locking said last named operating means in any one of a number of intermediate positions.

Signed at New York city, in the county and State of New York, this 15th day of May, A. D. 1931.
